MONROE H. DANIELS, OF HEWLETT AND JOHN A. SLACK, OF NEW YORK, N. Y., ASSIGNEES
TO PHOTOMATON, INC., OF NEW YORK, N. Y., A CORPORATION OF NEW YORK

PHOTOGRAPHIC DEVELOPER TANK LIQUID CIRCULATING SYSTEM

Application filed March 20, 1929. Serial No. 348,399.

The object of the present invention is to provide means for circulating washing and cooling liquid, as for example water, to the developer tanks of an automatic photographic apparatus, such as disclosed in United States Patent No. 1,656,522, dated January 17, 1928. In such developer apparatus a plurality of tanks, separated by vertical partition walls, are arranged in a casing and a sensitized strip 5 is passed through the successive tanks in order that the strip may receive the various developing, washing and other treatments. In order to maintain the chemicals cool, coils or bends of pipe may be placed in the chemical tanks and water circulated therethrough. 10 In the washing tanks water may be sprayed onto the moving strip. In prior devices of this kind the water after the washing operation passes to the bottom of the tank to be 15 thence carried away through drain pipes. It is the primary object of the present invention to conserve this water by recirculating a proportion of it in such manner as to maintain a required purity of the water which is 20 actually sprayed or otherwise applied to the sensitized strip, and the cooling water also is utilized, after the cooling operation, as means for raising the purity of the water leaving the washing tank. 25 A further and very important function of the recirculating system is that it automatically equalizes the temperature in the chemical solutions and in the wash water so as to 30 protect the emulsion on the strip from sudden temperature changes.

The invention will be described with reference to the accompany drawing, in which—

Figure 1 is a view in elevation, partly in section, of an embodiment of the invention, 40 and

Figure 2 is a partial elevation, largely schematic, of a developing tank casing, the division walls of the tanks being indicated by dotted lines.

Referring to the drawing A indicates a

developer tank casing, six compartments or tanks being shown separated by the division walls 1, three of the tanks, to wit those indicated at 2, 3 and 4 being washing tanks. Each washing tank at its base communicates with a pipe 5 leading to a manifold 6. Manifold 6 communicates with a pipe 7 connected with a branch pipe 8 discharging at 9 into the base of supply tank 10. Branch pipe 8 also communicates with a discharge pipe 11. 50 By closing valve 12 and opening valve 13 the wash water from tanks 2, 3 and 4 will be caused to flow through pipe 8 and into tank 10, a reverse adjustment of the valves causing water to flow directly into the discharge 55 pipe 11.

The cooling coils have been shown diagrammatically at 36, Fig. 2. It will be understood, however, that they will be located in the chemical tanks intermediate the wash tanks and that the water, after circulating, 60 will be discharged into the manifold 6.

Within the tank 10 and above the level of the discharge end of pipe 8 is the intake 14 of a pump 15 discharging through valve 16 into pipe 17. Pipe 17 is provided with a control valve at 18 and thence extends to a branch pipe 19 provided with a valve control 20. Branch 19 is connected by pipes 33, 34 to the discharge members, 75 such as atomizers 35, located within the washing tanks 2, 3 and 4. Above branch pipe 19 is a pipe 17a which may be connected to pipe 17aa leading to the cooling coils for the chemical tanks. A valve 21 may be provided for 80 shutting off 17a from pipe 17.

A fresh water pipe 22 is provided which communicates via pipe 23 with a pipe 24 extending within the tank and connected to a discharge nozzle 25 having its discharge end 85 located at the base of tank 10. The discharge nozzle is controlled by a valve 26 actuated by a lever 27 through the movement of a float 28. Within tank 10 near its open end is an outlet duct 29 communicating with a 90

discharge pipe 30. Duct 29 is below a larger discharge duct 31.

In the operation of the device duct 29 will be proportioned, as to outflow of water with-
5 in tank 10, in accordance with the fresh water admitted through pipe 25 and the flow of fresh water can be controlled by a valve 32 in pipe 24. The action of pump 15 in with-
drawing water from tank 10 and passing it
10 to the spray tubes and cooling coils will be proportioned to the flow of water from the washing tanks and cooling coils through pipes 5, 7 and 8 and thence into the tank. It will also be understood that the constant
15 flow of cool water into the tank will cause constant reduction of the temperature of the wash and cooling water entering the tank through nozzle 9. The warmer water discharged into the tank through nozzle 9 will
20 have a tendency to rise through the cooler surrounding water and a proportion of it will be drawn off through duct 29 for discharge via pipes 30 and 11. In practice, however, a greater proportion will remain in the
25 tank being circulated upward and downward by the thermal action to be passed by the pump back for the washing and cooling operation.

Having described our invention, what we
30 claim and desire to secure by Letters Patent
is as follows:—

1. In apparatus of the character described, in combination with a developer tank having compartments for wash liquid and chemicals, of a reservoir tank, means for circulating liquid from the reservoir tank to the wash liquid compartments and thence back into the reservoir tank, means including cooling conduits for circulating liquid from
35 the reservoir tank to the chemical compartments, and thence back into the reservoir tank, means for constantly withdrawing a predetermined amount of liquid from the reservoir tank, and means for constantly admitting a compensating amount of liquid to
40 the reservoir tank.

2. In apparatus of the character described, in combination with a developer tank having compartments for chemicals, and a reservoir
50 tank, means including a cooling conduit for circulating a cooling liquid from the reservoir tank to the developer tank in which the conduit is projected and thence back into the reservoir tank, means for withdrawing a predetermined amount of liquid from the reservoir tank and means for admitting a compensating amount of cooler liquid thereto.

3. In apparatus of the character described, in combination with a developer tank, and
60 a cooling member therein for receiving and enclosing a cooling liquid, of a reservoir tank, a conduit for the passage of liquid from the cooling member in the developer tank to the reservoir tank, a conduit for the passage of liquid from the reservoir tank to the cooling

member in the developer tank, a pump acting to withdraw liquid from the reservoir tank and pass it to the last named conduit, valve control means for admitting liquid to the reservoir tank independently of the developer tank and means independent of the developer tank for withdrawing liquid from the reservoir tank.

In testimony whereof, I have signed my name to this specification.

MONROE H. DANIELS.
JOHN A. SLACK.
